UNITED STATES PATENT OFFICE.

CHARLES HAMMER, OF HOLLIS COURT BOULEVARD, NEW YORK, ASSIGNOR TO AMERICAN METAL CAP COMPANY, OF BROOKLYN, NEW YORK, A CORPORATION OF NEW YORK.

LUG-FORMED CAP.

Application filed November 18, 1926. Serial No. 149,022.

- This invention relates to metal caps or closures and to the method of making the same and particularly to that style of cap commonly designated in the trade as "lug caps" for use on glass bottles or containers having spaced lugs or multiple or divided threads whereby on rotating or turning the cap it will be securely locked on the container, the object of the invention being to 5 provide an improved reusable metal cap or closure having a plurality of lug formed projections of improved construction whereby certain disadvantages heretofore present in these forms of caps are obviated.
- 10 The primary object of the present improvement is the provision of a rotary metal cap or closure having an improved form of locking or holding lug which will so engage or grip the glass threads of a container that 15 the scratching or cutting thereof is obviated, the present cap being an improvement upon my Patent No. 1,079,238 of November 18, 1913; and also Patents 1,440,990 dated January 2, 1923, and 1,560,569 of November 10, 20 25 1925. In all of these patents the lugs are pressed inwardly from the bead or rolled edge in such manner that they do not conform to the contour of the container and have the inner face thereof straight and 30 more or less sharp with the result that the center only of this straight edge of the lug rubbed against the glass container immediately under the threads acting very similar to a glass cutter scratching and marking 35 the container thread so that the thread or portions thereof at times broke off, and sometimes these particles of glass would get into the contents of the container making it impossible to use it. For some reason 40 45 these objectionable features occurred most frequently in those caps having only a pair of lugs instead of four.
- The object of the present invention therefore is the provision of a cap or closure member having a construction of lug which is an improvement upon the lugs of the 50 55 60 65 70 75 80 85 90 95 100 lugs to come into engagement suddenly on a small part only of the brittle glass thread and scratched and weakened it so that in the handling of the container thereafter and in 5 the reuse of the cap portions of the glass thread would break off especially when the glass threads are unusually brittle as is sometimes the case and the caps are quickly turned on.

10 In view of the fact that millions of glass containers are capped and handled per day usually by machinery and that frequently some have the threads much more brittle than others it will be realized that any improvement that will avoid cutting or scratching of the glass thread and the consequent breaking off thereof is an important one.

In the drawings accompanying and forming 20 a part of this specification, Fig. 1 is an enlarged perspective view illustrating a small size two lug metal cap of this improved construction; Fig. 2 is an inside view of the cap; Fig. 3 is a detail enlarged view 25 of a portion of the cap illustrating one of the improved lugs; Figs. 4 and 5 are sectional views taken respectively on lines 4—4, 5—5 of Fig. 2; Fig. 6 is a view of this improved cap applied to a glass container; Fig. 30 7 illustrates a portion of the roll which may be used for forming the lugs on the bead or rolled edge of the cap; and Fig. 8 is an enlarged detail view of one of these improved lugs.

35 Similar characters of reference indicate corresponding parts in the several views.

Before explaining in detail the present improvement and mode of operation thereof, I desire to have it understood that the 40 invention is not limited to the details of construction and arrangement of parts which are illustrated in the accompanying drawings, since the invention is capable of other embodiments, and that the phraseology 45 which I employ is for the purpose of description and not of limitation.

This improved cap when of a small size is provided with a pair of diametrically opposite lugs but the cap may have any desired 50 number of lugs according to the size thereof, the larger sizes of caps usually having four lugs. In the metal cap as shown it comprises a top 2 having a depressed groove 3 for contact with a suitable liner 4 for sealing 55 the top of the container. This top constructed in any suitable way is provided with a depending flange or skirt 5 shown of corrugated form, the corrugations 6 not only forming a means for gripping the cap in 60 the handling thereof but acting as a reinforcing means to stiffen both the flange and the lug. They also provide an efficient means for the proper formation of the cap on the forming rolls. The edge of the skirt 65 is strengthened by beading, rolling or

curling it, as shown outwardly and upwardly to form a reinforced bead or curled edge 7 and this bead not only gives a pleasing appearance to the cap but it prevents cutting of the hands of the user and also provides a sanitary cap in that the raw edge is sealed and protected against corrosion and acids and the action of the elements. It is also particularly useful in strengthening the flange and the lug itself while providing means for forming the lugs therefrom at the lower edge of the skirt whereby they have increased strength and holding efficiency.

At a plurality of places shown as two in the form of cap shown this reinforced bead or curled edge is pressed or inset inwardly toward the center of the cap to form inwardly extending lugs 8 which on their inner edges are curved or concaved lengthwise thereof as at 9 or circumferentially between the ends of these lugs to substantially conform to the curvature of the glass container and to the general curvature of the bead, the length of the curve however being less than that of the bead but sufficient considering the short length of the lugs to conform to the general curvature of the glass container. This inwardly pressing and curvature of the lug is obtained by insetting or pressing the bead radially inward without materially deforming it while exerting a greater pressure at the opposite ends of the lug as at 10 and 11 and at the same time somewhat flattening these ends of the lug with the result that the lug is tubular in cross section at its center which tubular formation also extends toward the ends so that the under side or thread engaging face of the lug as 12 is of round or curved or beveled formation while the lug is also curved lengthwise thereof along its inner edge forming an arc less than that formed by the major part of the beaded edge since the curved inner edge of the lug is inside of and therefore substantially concentric with the curved inner edge of the bead. In other words the bead of the cap has an inside diameter sufficiently large to permit it to pass over the threads or lugs on glass containers, while the diameter of the curved faces of the lugs is less, but sufficient to permit it to pass over the neck or mouth of the container, the outside diameter of which usually coincides with that at the inner or base of the threads or lugs of the container.

In the manufacture of these caps a flanged hat-shaped blank is first formed and the flange of this blank is then by suitable pressure curled or beaded. In practice this curling or beading is usually done on the same machine that forms the lugs and when this is the case the flanged hat-shaped blank is suitably supported on a chuck head and this head is provided with a plurality of recesses corresponding in number to the number of

lugs the cap is to have and it is into these recesses that the beaded portions of the cap are pressed to form the arc or crescent-shaped lugs. When the lugs are to have a tapered or inclined under or thread engaging face substantially corresponding with the inclination of the glass thread, then the side walls of these chuck recesses are tapered or inclined so that the tail end of the lug as it is turned on to the jar will be closer to the top of the cap than will the front end, and the punches or tools which cooperate with this recessed chuck may also be made tapered or inclined transversely thereof. Consequently when the bead of the cap is pressed radially inward by the punches hereinafter described and which punches have a concaved end, it follows that greater pressure is exerted at the spaced points or ends of the lugs than intermediate such ends and as the metal of which the lugs are thus formed is forced radially inward into the recesses of the chuck, it is also forced transversely of this inward movement so that when the chuck recess is provided with the inclined or tapered side wall herein before referred to, it follows that the under or thread engaging face of the lug in the direction of its length is provided with an inclined or tapered face 13, so that it substantially conforms to the inclination of the glass threads or lugs. Thus the lugs will engage under the glass threads throughout their entire lengths with their concaved inner faces conforming to the curvature of the glass container. The curved formation of the lugs crosswise thereof also assists in preventing any cutting or scratching the glass thread.

From the foregoing it will be observed that the lug is formed by pressure exerted upon the bead of the skirt sufficient to press this bead inwardly the desired extent without however materially deforming the lug between its ends or that part of the bead at either side of the lug. In other words, a part of the bead is inset from the rest of the bead, but in such manner that the inner face of the inset part is arc or crescent shaped instead of straight while the lug retains its tubular formation so that it is also of curved formation crosswise thereof. The pressure upon the lugs is radially inward and also to a certain extent vertically or transverse of this radial inward pressure, that is, toward the top of the cap, this being more particularly so at the ends of the crescent or arc-shaped lugs and as this pressure is greater at the ends of the crescent, it follows that a crescent shaped or concaved formation of closed or multi-walled lug is obtained, the major portion of which, however, is preferably tubular, and owing to the vertical or transverse pressure, it follows that when the chuck recess has an inclined or

tapered side wall, the under or thread engaging face of this tubular lug is likewise inclined or tapered in the direction of its length to conform to the incline or taper of the glass thread and consequently an improved form of locking lug is obtained, tubular in cross section and curved in the direction of its length and also curved in cross section with a tapering thread engaging face in the direction of its length.

I believe that I am the first to provide a metal cap or closure having a combined curled or beaded lower edge and a lug of the form shown and described herein whereby the lug is of curved or concave formation between its ends and is also tubular between its ends whereby it will firmly hold on the container and at the same time eliminate the scratching and marking of the glass threads.

By having the lug of tubular formation the lug is not only strengthened, this being materially assisted by the corrugations 6 above the lug which may run from adjacent to the top of the lug toward the top of the cap but the cap can be made of relatively thin sheet metal or of any other suitable material and yet have sufficient strength and resistance to resist any strain that may be placed upon the cap in the handling thereof.

From the foregoing it will be observed that this improved lug engages the glass threads practically throughout the entire length of the tapered face of the lug while conforming to the general curvature of the glass container under the thread and that it has no sharp straight cutting edge for engagement with the glass container so that there is no liability of the thread being cut or marked and that further owing to the tubular formation of the lug it has a certain resilient or spring action so that when turned on to the thread of the container it will compensate for any inequalities or variations at the under side of the thread, in other words, it can be applied with a cushioning effect.

The cap turns on very easily and with a gradual gripping effect without any cutting or marking of the glass container or thread and although it can be turned off easily yet it grips the thread effectively so that the cap will not jar off in the ordinary handling of the container while the cap is firmly drawn down to insure a tight seal between the liner and the mouth or upper edge of the container.

It will be understood, of course, that the lug may be formed arc-shaped without the necessity of forming the under or thread engaging face tapered. In other words, it is not necessary that the lug have a tapered under face or be actually hollow or tubular in order to give it an arc-shaped form, but it is highly desirable that it have this tapered face where the lug is to grip the glass thread

throughout the entire length of the lug. The tubular form is preferable, although the multi walls of the lug may be more or less compressed and somewhat flattened if preferred. As hereinbefore stated, in the formation of this improved cap, a hat shaped blank is first formed having an outwardly turned flange of suitable width and this flange is by suitable tools or punches gradually, as step by step, bent or curled to form a coil or bead. In practice this is usually done in the same machine which is utilized to form the lugs and when this is the case the cap is supported on a recessed chuck having recesses corresponding in number to the number of lugs the cap is to have. The flange is then by suitable forming tools curled or beaded and this curled or beaded edge is at intervals subjected to suitable punches or tools, a form of which is shown at 20, Fig. 7, in which the end of the punch is concaved or crescent shaped so that the spaced points of this punch will press the metal farther inward than it is pressed intermediate these points and in consequence the bead of the cap is inset to form the closed and multi-walled or tubular lugs hereinbefore described. As the ends of the crescent formed lugs are pressed inwardly to a greater extent than that portion of the lug intermediate the ends, it follows that greater pressure is exerted at the ends of the crescent shaped lug so that they are deformed; and when as hereinbefore stated the recessed portions of the chuck have a tapered or inclined wall, it follows that this radial inward pressure forces the metal vertically into this recess since it must, owing to the deformed ends of the lugs, flow in this direction and therefore the under faces of the lugs are inclined or tapered conforming to the inclination or taper of the side wall of the chuck recesses.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A metal closure for glass containers comprising a top having a depending skirt provided with a closed lug having a concaved inner face.

2. A metal closure for containers comprising a top having a depending skirt provided with a tubular lug having a concaved inner face.

3. A metal closure for containers comprising a top having a depending skirt provided

with a tubular lug having a concaved inner face, said lug being tapered in the direction of its length on its under face.

4. A metal closure for glass containers comprising a top having a depending skirt provided with a beaded or curled lower edge having thereon at intervals a plurality of tubular formed lugs having concaved inner faces in the direction of their length. 70

5. A metal closure for glass containers comprising a top having a depending skirt provided with a beaded or curled lower edge having thereon at intervals a plurality of tubular formed lugs concaved at their inner faces in the direction of their length, each of said lugs having a tapered under face. 75

6. A metal closure for glass containers comprising a top having a depending skirt provided with a beaded or curled lower edge having at intervals lugs of tubular formation combined with the bead, said lugs being concaved in the direction of their lengths on their inner faces and curved or beveled crosswise thereof on their under faces. 80

7. A metal closure for glass containers comprising a top having a depending skirt provided with a beaded or curled lower edge having at intervals lugs of tubular formation combined with the bead, said lugs being concaved in the direction of their lengths on their inner faces and curved or beveled crosswise thereof on their under faces, each of said lugs also having an inclined or tapered formation on its under face in the direction of its length. 95

8. A metal cap having a depending skirt provided with a strengthened curled or beaded lower edge having formed therewith inwardly extending locking lugs each having a curved inner face conforming substantially to the general curvature of the container. 100

9. A metal cap having a depending skirt provided with a strengthened, curled or beaded lower edge having combined therewith inwardly extending tubular locking lugs inset from the bead and each comprising a pair of depressed portions spaced apart by a curved or arc shaped tubular portion having its inner edge conforming substantially to the general curvature of the container. 110

10. A metal cap having a depending skirt provided with a strengthened, curled or beaded lower edge having combined therewith inwardly extending tubular locking lugs inset from the bead and each comprising a pair of depressed portions spaced apart by a curved or arc shaped tubular portion having its inner edge conforming substantially to the general curvature of the container, and each of said lugs being tapered in the direction of its length on its under side. 120

11. A rotatable metal cap for glass con- 125

- tainers comprising a top having a depending skirt provided with a beaded or curled lower edge, said edge being inset at intervals to form a plurality of closed arc shaped lugs each having a concaved inner face forming an arc less than the arc of the major portion of the bead. 12. A rotatable metal cap for glass containers comprising a top having a depending skirt provided with a beaded or curled lower edge, said edge being inset at intervals to form a plurality of tubular formed arc shaped lugs each having a concaved inner face forming an arc less than the arc of the major portion of the bead, each of said lugs terminating at its ends in a pair of deformed portions. 13. A rotatable metal cap for glass containers comprising a top having a depending skirt provided with a beaded or curled lower edge, said edge being inset at intervals to form a plurality of closed arc shaped lugs each having a concaved inner face forming an arc less than the arc of the major portion of the bead, each of said lugs terminating at its ends in a pair of deformed portions, and having a tapered under face. 14. The method of making lug formed caps which consists in first forming a flanged hat shaped blank and then pressing the flange of such blank radially inward to form a coiled, beaded or curled lower edge and therefrom a plurality of inwardly extending tubular lugs inset from the bead and each having a concaved inner face, the arc of which is less than that of the major portion of the bead. 15. The method of making lug formed caps which consists in first forming a flanged hat shaped blank and then pressing the flange of such blank radially inward to form a coiled, beaded or curled lower edge and therefrom a plurality of inwardly extending tubular lugs inset from the bead with deformed ends and each having a concaved inner face, the arc of which is less than that of the major portion of the bead, and a tapered under face. 16. A cap having a combined beaded edge and lug, said lug comprising an inwardly extending closed projection having a concaved inner face substantially conforming to the convex outer face of a container neck. 17. A cap having a combined beaded edge and lug, said lug comprising an inwardly extending closed projection having a concaved inner face substantially conforming to the convex outer face of a container neck, said lugs being inset relatively to the bead with the concaved inner face substantially concentric with that of the bead. 18. A cap having a combined beaded edge and lug, said lug comprising an inwardly extending tubular projection having a concaved inner face substantially conforming to the convex outer face of a container neck. 19. A cap having a combined beaded edge and lugs located at intervals therearound, said beaded edge having a diameter at least as great as that of the outer faces of the container threads or lugs and said lugs each having a concaved inner face, the diameter of said concaved faces being less than that of the bead whereby said concaved inner faces are substantially concentric with the bead. 20. A closure member having a depending skirt provided with a bead, said bead having at intervals locking lugs or projections, each having a concave inner face of substantially crescent shaped form conforming substantially to the convex outer face of a container neck below the thread or neck of such container. 21. A closure member having a depending skirt provided with a strengthened portion or bead and reinforcing means or corrugations, said bead having at intervals locking lugs or projections, each having a concave inner face of substantially crescent shaped form conforming substantially to the convex outer face of a container neck below the thread or neck of such container.

Signed at 1822 Park Row Building, New York city, N. Y., this 17th day of November, 1926.

CHARLES HAMMER.
